UNITED STATES PATENT OFFICE.

RALPH CROVER, OF SPRINGFIELD, MISSOURI.

POLISHING-BRUSH.

No. 884,363.

Specification of Letters Patent.

Patented Oct. 30, 1906.

Application filed October 28, 1905. Serial No. 284,869.

To all whom it may concern:

Be it known that I, RALPH CROVER, a citizen of the United States, residing at Springfield, in the county of Greene and State of Missouri, have invented new and useful Improvements in Polishing-Brushes, of which the following is a specification.

My invention relates to improvements in blacking and polishing outfits for shoes, &c.

It has for its object, principally in blacking and polishing shoes, to obviate the handling of the "blacking" or bottled liquid, and therefore prevent the soiling of the hands, the carpets, and floor, as well as to dispense with the use of an ordinary dauber, sponge, or cloth, permitting the direct application of the blacking or polishing liquid from the "original package" to the shoe, and also to avoid the dipping or daubing the brush into the blacking or liquid, as heretofore practiced, and to carry out the aforesaid objects in a simple, economic, and effective manner.

Said invention consists of certain structural features, substantially as hereinafter fully disclosed, and particularly pointed out by the claims.

In the accompanying drawings, illustrating the preferred embodiment of my invention, Figure 1 is a side elevation thereof. Fig. 2 is a longitudinal section taken vertically through the polisher. Fig. 3 is a perspective view of the original package or incased cake or quantity of blacking as adapted for use in connection with the brush or polisher. Fig. 4 is a modification of the invention for the application of the polishing material or blacking in liquid form, the closure or cover being thrown "back" and limited in movement by a stop suitably secured in position. Fig. 5 is a view of an ordinary form of blacking-brush with my invention applied thereto.

In carrying out my invention I provide a suitable stock 1, preferably of wood, and adapted in outline for convenience of grasping by the hand, having, preferably, plane lateral surfaces and lower opposite sloping surfaces 1^a 1^b. The less sloped or inclined forward surface 1^a has fixed thereto a brush proper, 2, the purpose of which is apparent, especially to those who use the same in plying their vocation. The other or greater inclined surface 1^b has applied thereto what may be termed the "polisher" 3. The latter is formed, preferably, of several layers or thicknesses of cloth or woolen material 3^a

and a piece of suitable textile material, as cotton fabric 3^b, preferably doubled upon itself and covering the bottom layer of cloth. The end portions of said cotton piece or fabric are folded inward and reinforced and suitably secured to the stock 1, transverse pieces or strips 3^c, preferably of wood, being laid upon said end portions and the end portions of one or more of said woolen or cloth layers being laid upon said wooden pieces, 65 while plates or metal pieces or strips 3^d are finally laid upon the latter and the whole suitably fastened to the stock by driving nails or inserting other fastenings therethrough. It will be noted that any other 70 way of securing the several parts named to the stock may be adopted which may be practicable. It will be observed that the short brush for imparting the preliminary brushing or polishing action to the object to 75 be treated and the polisher proper are arranged or disposed in opposite inclinations, being applied, as above noted, to the opposite sloping surfaces of the stock 1 to permit their separate or independent use, as will be readily appreciated.

A cake of blacking 4, incased in what I term "filter" or highly-pervious cloth 4^a to permit the ready expressing of the blacking therethrough for its required application 85 when used, is suitably secured to the top surface of the stock 1 at its forward end. Said cake of blacking is spread upon a plate 4^b, constituting a bottom member, which has suitable screw connection 4^c with a head 90 5, secured upon the stock 1, said head being inclined downward and forward upon its upper surface for the proper presentation of the cake of blacking in applying it to the shoe or object for polishing. With the blacking 95 thus spread upon the plate 4^b the edges of the incasing wrapper or cloth 4^a of the former are folded or tucked in under said plate, and thus clamped in place by the aid of the same fastening effecting connection between said 100 plate and the head. The package of blacking thus constituted and connected to the brush may be termed the "original package," it being applied directly to the shoe or object to receive the polish by suitably manipulating the brush, as well understood. Thus 105 there is no need for handling the blacking, consequently avoiding the soiling of the hands. Also the use of a dauber, sponge, cloth, or other separate means for applying 110

the blacking is obviated. Hence there is no liability of the soiling of the carpet or floor in the polishing operation, as heretofore experienced with the use of the ordinary blacking-brush.

5 In the modification as disclosed by Fig. 4 a receptacle or box 6 is employed for holding the polishing material when in the form of a liquid, said box having a hinged cover 6^a to protect the liquid as against evaporation when the same is not being applied or used. Said cover is held when in "open" position by a spring-stop 6^b, secured to said cover and having its free end adapted when the latter is thrown back to engage a notch in between the head 5 and the stock 1, as shown.

10 In the modification as shown in Fig. 5 the original package of blacking or polishing material 4 is shown as applied to the usual 15 disk or circular head 7 of the ordinary form of blacking-brush, as will be readily appreciated.

I claim—

1. A polishing-brush provided with an 25 "original package" of blacking or polishing

material, and a pervious wrapper containing the latter.

2. A polishing-brush provided with a cake of "blacking" and a pervious wrapper containing the latter.

3. A polishing-brush provided with a plate, a cake of "blacking" spread upon said plate and a pervious cloth or wrapper, inclosing said cake of blacking with its edges folded or tucked in place under said plate 35 and means for securing the latter to the brush-stock.

4. A polishing-brush provided with a quantity of polishing material and having its stock or portion gripped by the hand provided with a head, a receptacle secured to said head and having a hinged cover, and a pervious wrapper inclosing said quantity of polishing material.

40 In testimony whereof I affix my signature in presence of two subscribing witnesses.

RALPH CROVER.
